UNITED STATES PATENT OFFICE

2,605,095

ENGINE GOVERNOR WITH MODIFIER

Clifford L. Muzzey, Lexington, Mass., and Howard Carson, Seattle, Wash., assignors to General Motors Corporation, Detroit, Mich., a corporation of Delaware

Application April 8, 1948, Serial No. 19,714

10 Claims. (Cl. 264—3)

1

This invention relates to an internal combustion turbine engine and propeller power plant for aircraft use.

An object of the invention is to provide a propeller pitch controller which is manually adjusted for various speeds and which will maintain the selected speed with the minimum of hunting. To accomplish this object, the invention includes means responsive to speed error, means responsive to the rate of change of speed error and blade pitch setting apparatus which is operated in response to the combined effects of said means whereby the rate of change of blade pitch is proportional to speed error and to the rate of change of speed error. Both said means contribute to the combined effect in proportions which are varied according to the blade pitch required for the selected speed. Concurrently with manual adjustment of the controller to maintain a selected speed, the controller is manually adjusted to obtain approximately the blade pitch required for the selected speed; and the blade pitch is accurately set automatically.

Further objects and advantages of the present invention will be apparent from the following description, reference being had to the accompanying drawings, wherein a preferred embodiment of the present invention is clearly shown.

In the drawings:

Fig. 1 is a view looking toward the propeller end of an internal combustion turbine engine (engine shaft in section) and shows means for mounting and driving the blade pitch controller and manually operated means for controlling blade pitch.

Fig. 2 is a view in the direction of arrow 2 of Fig. 1 and shows the controller in the direction of arrow 2A of Fig. 5.

Figs. 3 and 4 are sectional views respectively on lines 3—3 and 4—4 of Fig. 1.

Fig. 5 is a view of the controller in the direction of arrow 5 of Fig. 2.

Fig. 6 is a sectional view on lines 6—6 of Figs. 2, 4 and 8.

Fig. 7 is a sectional view on line 7—7 of Fig. 10.

Fig. 8 is a sectional view on lines 8—8 of Figs. 5 and 6.

Fig. 9 is a sectional view on line 9—9 of Fig. 8.

Fig. 10 is a sectional view on lines 10—10 of Figs. 5 and 6.

Fig. 11 is a view in the direction of arrow 11 of Fig. 6, showing sections of certain parts on line 11—11 of Fig. 12.

Fig. 12 is a sectional view on lines 12—12 of Figs. 2 and 11.

2

Fig. 13 is a sectional view on line 13—13 of Fig. 15.

Fig. 14 is a sectional view on the line 14—14 of Fig. 11.

Fig. 15 is a sectional view on the line 15—15 of Fig. 11.

Fig. 16 is a diagram of the controller.

Fig. 17 is a sectional view in perspective of a propeller assembly with which the controller is adapted to be used.

Fig. 18 is a fragmentary sectional view on line 18—18 of Fig. 17.

Figs. 19, 20 and 21 are sectional views taken respectively on lines 19—19, 20—20 and 21—21 of Fig. 18.

Fig. 22 is a fragmentary view in the direction of arrow 22 of Fig. 21.

Referring to Figs. 1 and 2, the engine frame E supports a plate 25 and a sheet metal cover

26 attached by studs 27, nuts 28 and rivets 29 (Fig. 4) secure the cover 26 to the plate 25. Controller C has a housing 100 which is attached to the plate 25 by screws 30 (Fig. 1). Engine shaft S (Fig. 4) drives a propeller assembly PH 25 and a gear 31 meshing with an idle gear 32 which drives a gear 110 attached to the drive shaft 111 of the controller C.

A housing 100 is provided with a top cover 101 (Fig. 6) and a bottom cover 102 and with

a thick walled partition 103 between the covers. The spaces between the partition 103 and covers contain oil and are connected by passage 104 (Fig. 7). Cover 102 provides a circular flange 105 which is received by a hole 106 in plate 25 (Fig. 4). Engine driven gear 110 drives shaft

111 journaled in a bearing sleeve 112 supported by the partition 103. The escape of oil from the reservoir 104b around the shaft 111 is prevented by a shaft seal of the ground surface type comprising a plate 113 with screws 114 attached to the cover 102. Plate 113 retains a seal ring 115. Plate 113 is engaged by the angular boss 116 of a sleeve 117 urged downwardly by a spring 118 which urges upwardly a washer 119 against the lower end of bearing sleeve 112.

The upper end of shaft 111 provides a gear 120 meshing with a gear 121 provided by plate 122 carrying a housing 123 which encloses a governor comprising weights 124 connected by strap hinges 125 with the plate 122. The weights 124 are connected by a flexible metal stirrup 126 which extends through notches in a plate 127 connected with a spool valve 128 having a land 129 and annular groove 130 connected by a cross 55 passage 131 with a hole 132. The governor

spring 135 is confined between a retainer 136 and a retainer 137 which bears against the outer race of a ball bearing 138 whose inner race bears against the plate 127. The upper end of valve 128 is threaded to receive a nut 139 which when tightened forces a washer 140 against the inner race of bearing 138 and the latter against the member 127 and it bears against washer 141 which engages a shoulder provided by the valve 128.

The hub of gear 121 is cup-shaped to receive a bearing bushing 144 which is journaled on a sleeve 145 received by a hole 146 in the partition 103 (Fig. 12). The sleeve 145 supports seal rings 147. The lower surface of the hub of gear 121 engages a bearing plate 148 which is supported by plate 149. Plate 148 is retained by a plate 150 with the screws 150a (Fig. 8) attached to the partition 103.

Between the sleeve 145 and the spool valve 123 there is located a sleeve valve 151 having an annular groove 152 with cross passages 153 connected to the interior of the sleeve. Groove 152 is in communication with cross passages 154 of sleeve 145 which are connected with annular groove 155. Sleeve valve 151 provides port 156 controlled by the land 129 of valve 123 and in communication with an annular groove 157 with cross passages 158 of sleeve 145 connected with annular groove 159.

The speed for which the governor is set is determined by the position of lever 160 (Figs. 5 and 8) which has a hub flange 161 of arcuate contour (Fig. 8) connected with and adapted to push on tangs 162 and 163 of discs 164 and 165 respectively attached to the end turns of a clutch spring 166. These tangs are engageable with the arcuate hub flange 167 of a hub 167a which a key 167b connects with a shaft 168 journaled in a tube 169 integral with a plate 169b which screws 169a attach to the housing 100 (Fig. 5). Shaft 168 is also journaled in a bushing 168a supported by the housing 100. There is a seal ring 168b between the shaft 168 and the tube 169 and a seal ring 169c between the tube 169 and the hub 161 of lever 160 and a seal 161a between hub 161 and a bearing 170 in which the hub 161 is journaled. The lever 160 can rotate the shaft 168 in either direction because the action of hub flange 161 is to unwind spring 166 and cause it to connect 161 with flange 167; but shaft 168 cannot back up and operate lever 160 in either direction because the tendency of flange 167 is to wind up the spring 166 and cause it to grip the tube 169.

Shaft 168 extends through a sleeve 172, shim washers 173 and the hub 174 of a lever 175 retained by a washer 176 and a nut 177 threadedly engages shaft 168. A key 178 connects the hub 174 with shaft 168. Lever 175 carries a pin 179 carrying a roller 180 for engaging a lever 181 which, through a cross pin 182, is connected with the spring retainer 136. Lever 181 has a bifurcated portion 183 connected by a pin 184 with a nut 185 threadedly engaged by a screw 186, the reduced lower end portion 187 of which is received by a socket 188 in the housing 100 and the upper end of which extends through a hole 189 in the housing where it supports a seal ring 190. Screw 186 has a serrated flange 191 adapted to engage a similar flange 192 provided by plate 193 which screws 194 (Fig. 5) attach to the housing 100. A screw driver applied to the notch 195 in the upper end of screw 186 is pushed down to move the nut 185 down against the action of spring 135 and thereby disengage the flange 191

thereof from the flange 192 of plate 193. While the screw 186 is thus disengaged from the plate 193, the screw is turned in order to change the position of nut 185 relative to the screw 186. 5 When the screw driver is elevated the screw 186 moves up to cause flange 191 to engage the flange 192, thereby holding the screw 186 against rotation. The adjustment of the position of nut 185 is factory set and the initial adjustment is left 10 undisturbed. The control of spring 135 is effected by means of the lever 160.

The housing 100 is filled with oil to about the level of the lower edge of the filler opening 200 which is closed by a plug 201. The governor weights 124 are submerged. Agitation of the oil by the weights is reduced by the cylindrical housing 123 which surrounds it.

The gear 121 drives a gear 205 connected with the drive 206 (Fig. 8) of a gear pump having a gear 207 meshing with a gear 208 (Fig. 7). A pipe 209 (Fig. 8) conducts oil from the housing to the pump inlet. The pump outlet is connected with a passage 210 in the partition 103 and connected with a bore 211 which receives sleeve 212 retaining a seal ring 212a. Sleeve 212 provides a cylinder 213 which receives a piston 214 connected by its rod 215 with a notched disc 216. A compression spring 217 is located between the sleeve 212 and the disc 216 and urges the latter upwardly so that the piston 214 blocks the escape of oil from port 218 in sleeve 212 and to an annular groove 219 of the sleeve connected with a passage 220 which is connected with the oil reservoir. When the oil pressure increases to a certain amount, the pressure upon the shoulder of the piston valve 214 becomes sufficient to overcome the spring 217 whereupon the piston 214 moves down to permit some oil to escape from the bore 210 to the port 218. In this way the pump pressure is limited to a certain value. Sleeve 212 is retained by a plate 221 with screws 222 attached to the partition 103. Plate 221 has a hole 223 for the escape of oil which might otherwise be trapped in the lower end of cylinder 213.

Partition 103 has a bore 230 which receives a sleeve 231 retaining seal rings 232. Sleeve 231 is retained by a plate 233 which a screw 234 (Fig. 8) attaches to the partition 103. Sleeve 231 receives a spool valve 235 having a land 236 and a guide flange 237. Sleeve 231 has an annular groove 238 connected by passages 239 with the interior of the sleeve and thence to the space between the land 236 and the flange 237. The land 236 controls port 240 connected with annular groove 241 of sleeve 231. If valve 235 moves up oil can escape from the ports 240 and return to the reservoir through the lower end of the sleeve 231. If valve 235 moves down the ports 239 and 240 will be connected. Position of valve 235 is controlled by a plate 242 which carries a screw 243 having a pad 244 against which the valve 235 is urged by a compression spring 245 bearing against the plug 246 in the sleeve 231 and against the flange 237 of valve 235. The screw 243 is retained in the desired position of adjustment by lock nut 247. A stud 250 threaded into the partition 103 passes through a hole in the plate 242 and is surrounded by a spring 251 which presses against the plate 242 and against a washer 252 retained by a nut 253 threadedly engaging the stud 250. The spring 251 presses the plate 242 against a pin 254 (Fig. 10) and against an adjustable pin 255 which can be inserted into one of a series of holes 256 in the partition 103. The location

of pin 255 determines the leverage of plate 242 relative to valve 235 which the screw 243 actuates, said leverage being the distance from the axis of screw 243 to a line joining the axes of pins 254 and 255.

A coil spring 260 (Fig. 10) received by socket 261 in the partition 103 surrounds a spring retainer provided by a stud 262 attached to plate 242. As viewed in Fig. 10, this spring 260 pushes the upper portion of plate 242 away from the partition 103 and toward the observer. This causes the plate 242 to engage a disc 263 (Figs. 6 and 10). Sleeve valve 151 is urged against plate 242 by leaf spring 264 which is attached to the plate. This spring extends into a notch 265 in the valve 151, said notch being cut into the bore in the valve so that oil can escape from the interior thereof through the oil reservoir. In Fig. 10, the point of engagement of plate 242 with the valve 151 is designated by the dot 266. The leverage of valve 151 with respect to the plate 242 is the perpendicular distance from the dot 266 to a line passing through the points of contact of plate 242 with the pins 254 and 255.

The disc 263 has a slot 270 which receives pin 271 which is carried by tube 273 guided by a bushing 274 which screws 275 attach to the housing 100. Tube 273 carries a seal ring 276 and the bushing 274 a seal ring 277. The bushing 274 provides diametrically opposite slots 278 and 279, the former receiving flats 280 provided by a flange of pin 271 and the latter receiving the pin itself. Thus the pin 271 and the tube 273 are non-rotatable. The left end of tube 273 is guided by a bushing 282 retaining a seal ring 283 and attached to the housing by screws 284. A spring 285 within the tube 273 bears against the tube and the bushing in order to move the tube toward the right, thereby causing the roller 286 journaled on a cross pin 287 supported by the tube to engage a cam 290 pivotally supported by a screw 291 fixed to a bracket 292 (Fig. 6) which screws 293 attach to the housing. Cam 290 has a lever arm 294 carrying a stud 295 pivotally supporting a roller 295a received by the radial slot 296 of a lever 297. Lever 297 has a hub 298 (Fig. 5) which a key 299 connects with a shaft 300 which is operatively connected with a lever 301 retained by nut 302 threaded on the shaft. Shaft 300 is journaled in the tubular part 303 of the housing 100 and is connected at its upper end by a key 304 with a hub 305 of a lever 306, said hub being retained by a nut 308 threaded on the upper end of shaft 300. Lever 306 has a lug 309 for a purpose to be described.

Lever 306 is received by the bifurcations 310 (Fig. 5) of rod 311 supported for a sliding movement by cylinder casting 312 which screws 313 attach to the housing 100. Rod 311 carries pins 315 and 316, the latter supporting a roller 317. Lug 309 of lever 306 (Fig. 8) is engaged by the head 320 of a screw 321 integral with a rod 322 which extends through a cylinder 323 which screws 324 attach to the housing 100. A spring 325 compressed between the end of the cylinder and a nut 326 threaded on screw 321 urges the lever 306 counterclockwise (Fig. 8) and clockwise (Fig. 10). Lock nut 327 retains nut 326 in the desired position of adjustment.

Spring 325 urges rod 311 to the right in Fig. 5 against a lever 330 pivotally connected by pin 331 with a piston rod 332 of a piston 333 within a cylinder 334 in the casting 312. At its right end (Fig. 10) the cylinder 334 is connected by

a passage 335 in casting 312 with a passage 336 in the housing 100. The left end of the cylinder 334 is connected by passage 337, annular groove 338 in cylinder 334 by passage 339 in the casting 312 with a passage 340 in housing 100. Any oil seeping past the piston rod 332 is received by an annular groove 341 connected by passage 342 connected with annular groove 343 of the cylinder 334, connected with passage 344 in casting 312 connected with passage 345 in housing 100 which leads to drain. The cylinder 334 is secured to the casting 312 by screw 346. Seal rings 347, 348 and 349 are provided as shown to prevent leakage of oil around the cylinder 334 and the piston rod 332 and the casting 312; and seal rings 350, 351 and 352 are provided as shown to prevent leakage of oil at the joints between the casting 312 and the housing 100.

The lever 330 is straddled by the bifurcations of lever 355 which a key 356 (Fig. 8) attaches to the shaft 168. A nut 358, threaded on the shaft, retains the lever 355. Pins 359 (Fig. 5), carried by the lever 355, provide journals for rollers 360 and 361 which engage a cam surface 362 provided by lever 330. In a certain range of operation, the surface 362 is engaged solely by roller 360 and in another range, it is engaged solely by roller 361.

When the lever 160 is moved clockwise (Fig. 5), from low speed position toward the higher speed position, lever 330 moves counterclockwise about its pivot 331 to cause the rod 311 to move toward the left or toward the right in Fig. 10. When the lever 160 is in position for selecting the lowest blade angle, the piston 333 will be in its leftmost position in Fig. 10 which would be rightmost in Fig. 5. Therefore, the rod 311 will be at its rightmost position in Fig. 5 and at its leftmost position in Fig. 10. Spring 325, acting through rod 311, tends to maintain the piston 333 in the position referred to.

Considering the servo piston rod 332 to be fixed for the moment, the actuator 160 calls for a blade angle corresponding approximately to a certain power requirement by moving the rod 311 and hence the lever 301. The piston rod 332 is caused to move in order to effect an accurate setting of the blade angle to maintain the speed for which the governor is set. This rod 332 is under control directly by the differential of pressures acting on opposite sides of piston 333. As will be explained later, the pump maintains a pressure on the left side of the piston and the pressure on the right side of the piston is under control by valve 235 and by a stabilizer which includes a cylinder 370 received within a recess 371 of the housing and sealed therein by a ring 372. At the top the cylinder is closed by a cap 373 having a passage 374 connected by passage 375 with the annular groove 159 of the sleeve 145. The lower end of cylinder 370 is connected by passages 380 and 336 with the annular groove 241 of sleeve 231 in which valve 235 is located and with the head end of cylinder 334. The pump is connected by passages 339 and 340 with the rod end of cylinder 334. Cylinder 370 receives a piston 390 connected by a rod 391 and a pin 392 with a lever 393 which is rigidly connected with the disc 263. Therefore the piston 390 controls the position of the plate 242 which controls the position of sleeve valve 151 and the position of the spool valve 235. Passage 381 connects the annular groove 155 of sleeve 145 (Fig. 6) with the annular groove 238 of sleeve 231 (Fig. 7). Passage 339 (Figs. 11 and 7) is connected with passage 210

which connects the pump with the pressure control valve 215 and with a filter chamber 400 (Fig. 6) containing a filter 401, the interior of which is connected by passage 402 with groove 155 of sleeve 145. Drain passage 345 (Figs. 10 and 11) is connected with passage 380.

Referring to Fig. 16, the rod M represents a manual operated member operated by the pilot. It moves a fuel control lever F and lever 160 (shown in two places in Fig. 16) which through lever 175 sets the governor spring 135, thereby selecting the speed which the controller is to maintain by control of blade angle through lever 301. Lever 160 also directly moves the lever 301 through the mechanism comprising lever 355, one of the rollers 360, 361, differential lever 330, rod 311, roller 317, lever 309 and shaft 300. Thus for any power demand indicated by scale N, there is a fuel setting and a speed setting and a blade angle setting indicated by scale B adjacent lever 301. If the blade angle set by rod M does not correspond with the speed setting of the governor, the controller makes the correction.

For any speed setting of the governor, the flyweights 124 have the same equilibrium position relative to their axis of rotation. Valve 128 has an equilibrium position blocking port 156 of sleeve valve 151. Piston 390 is in equilibrium position shown maintaining valve 151 in equilibrium position through the connection provided by lever 393 and plate 242 which spring 260 urges against the disc 263 while spring 264 urges the valve 151 against the plate 242. If the blade setting effected by rod M (acting through lever 355, a roller 360 or 361, lever 330, rod 311, lever 306, shaft 300 and lever 301) does not so control the engine that its speed corresponds with that for which the governor is set, the governor will sense the difference in speed or speed error, and move the valve 128. Any speed error results in movement of piston 390. The greater the error, the greater will be the displacement of piston 390 because it moves the valve 151 as a follow-up to bring its port 156 into alignment with the land 129 of valve 128. The rate of movement of the piston 390 is therefore proportional to the rate of change of speed error.

If the speed error is positive, port 156 is opened to drain through the bottom of valve 151 and pressure above piston 390 is relieved and piston 390 is moved up by oil flowing into the lower end of cylinder 370 through passage 380 connected by passage 336 with the right end of cylinder 334, said flow being caused by right movement of piston 333 under pump pressure on its left side. Because the rate of movement of piston 390 is proportional to the rate of change of speed error, the flow of oil through passage 380 to the cylinder 370 is proportional to the rate of change of speed error.

Since the displacement of piston 390 is proportional to the amount of speed error, the displacement of valve 235 (which is actuated by piston 390 through lever 393, disc 263 and plate 242, fulcrumed at 255), is proportional to speed error. As valve land 236 is displaced upwardly, oil flows from the right end of cylinder 334 through passage 336 and port 240 to drain at a rate proportional to speed error.

Consequently oil flows from the right end of cylinder 334 at a rate which is equal to the combined rates of flow through passage 336 to drain and through passage 380 to cylinder 370. The piston 333 moves right at a rate proportional to speed error and the rate of change of speed error

and a corresponding rate of movement is imparted to lever 301 through the mechanism which includes lever 330 fulcrumed on a roller 360 or 361, rod 311, lever 306 and shaft 300. Speed error is eliminated promptly without hunting by increase of blade angle since the controller is responsive to the amount of speed error and to the rate of change of speed error. When speed error has been eliminated, the piston 390 and the valves 128, 151 and 235 are in equilibrium position as shown in Fig. 16.

If the speed error is negative, the action is reversed. Valve 128 is lowered and oil is forced by the pump into the top of cylinder 370 and piston 390 moves down and valve 235 moves down to connect the pump with passage 336. Oil flows into the right end of cylinder 334 at a rate proportional to displacement of valve 235 downwardly which is proportional to speed error and at a rate proportional to the rate of flow out of the lower end of cylinder 370 through passage 380 which is at the rate of downward movement of piston 390 which is proportional to the rate of change of speed error. The effective area on the right face of piston 333 being greater than the left face area, the piston 333 is forced left at a rate proportional to the amount of speed error and to the rate of change of speed error. As piston 333 moves right, lever 330 moves clockwise about its fulcrum (one of the rollers 360, 361), rod 311 moves left under the action of spring 325 which rotates lever 306, shaft 300 and lever 301 clockwise to decrease the blade angle so that engine speed can increase.

When a sudden increase of power by increase of fuel and speed is demanded, control lever 160 is moved rapidly counterclockwise (Fig. 16) to increase suddenly the compression of governor spring 135 with the result that valve 129 is quickly moved below its equilibrium position which causes valves 129 to call suddenly for lower blade angle. There would be a "false" or over acceleration of the engine during the interim between the demand for a certain increase in speed and the return of valve 151 to equilibrium position were it not for the fact lever 160, acting through rod 311, lever 306, shaft 300 and lever 301, demands a higher blade angle. Conversely, when lever 160 is moved suddenly clockwise in response to demand for less speed and fuel and the compression of spring 135 is suddenly reduced, valve 129 moves up suddenly and calls for a high blade angle while lever 160, acting through rod 311, lever 306, shaft 300 and lever 301, demands a lower blade angle. Therefore, satisfactory governing action is obtained whether the movement of lever 160 is fast or slow.

The law of action of the controller is represented by $\beta = k_1 n + k_2 \dot{n}$ in which β is rate of change of blade angle. n is the amount of speed error, $\dot{n}$ is the rate of change of speed error, k_1 is the sensitivity constant of the governor and k_2 is the sensitivity constant of the acceleration responsive mechanism which includes the stabilizer piston 390. The constant k_2 is determined by the distance between the center line of pin 271 and the center line of valve 151 relative to the distance between pin 392 and pin 271. This relation is varied by changing the position of pin 271.

Fig. 10 shows that pin 255 may be placed in one of a series of holes 256 in partition 103. Fig. 16 shows the pin 255 supported by a bracket 255*j* with a screw 255*k*, passing through a slot in the bracket, attached to a support 255*l*. By mov-

ing the pin 255, the constant k_1 is changed. The constant k_1 is determined by the displacement of valve 235 for a given speed error. A change in k_1 does affect the relative stability which equals $k_2 - \sqrt{2Ik_1}$, I being a constant, but the primary effect of change of k_1 is to change the basic time constant of the control. A change in the position of pin 271 causes a pure change in stability without altering the time constant.

Analysis of the aerodynamic properties of the propeller indicates that different quantities of control damping (represented by k_2) are required for different blade angles. The demand for increased engine power which is satisfied by increase of burner fuel and increase of speed results in higher blade angle by means of which the power is absorbed. As blade angle increases, the slope of the curve of aerodynamic torque versus rotational speed increases. Since the slope of this curve represents the natural aerodynamic damping which the propeller contributes to the system, the constant k_2 can be decreased with increased power demand so that the total damping (control damping plus aerodynamic damping) will remain approximately constant. As shown in Fig. 16, as lever 301 moves up to increase blade angle, cam 290 is moved counterclockwise to permit spring 285 to move the fulcrum pin 271 to the right, thereby decreasing the ratio of the leverage of piston 390 with respect to pin 271 to the leverage of valve 151 with respect to pin 271. Because this leverage ratio decreases with increase of blade angle, the acceleration sensitivity coefficient k_2 decreases. Cam 290 is shaped to effect decrease of k_2 , with increase of blade angle according to a schedule suitable for the particular turbine-propeller power plant.

In the lower power range contact between lever 355 and lever 330 is made through roller 360 acting on cam surface 362. In the high power range, roller 361 engages cam 362 and takes over control to render the controller less effective under high power conditions since the aerodynamics of blade angle change under these conditions provide greater effect in the governing function.

As viewed in Fig. 1, lever 297 is urged clockwise by spring 325 (Fig. 8). Instead of using spring 325, a spring 410 connecting lever 301 with a bracket 411 attached to plate 25 can be substituted. A link 412 connects lever 301 with arm 541a of a ring gear 541 which is a part of the propeller hub assembly PH which will be described later. Gear 541 has an arm 541b carrying a pin 413 received by a slot 414 in a plate 415 attached to a tube 416 which telescopically receives a Bowden wire tube 417 which is fixed by a clip 418 to bracket 411. Tube 416 is guided by a bracket 419 attached to plate 25 and by the tube 417. Tube 416 is connected with a Bowden wire (not shown) within the tube 417. In case of failure of the controller, the rod can be manually operated to control blade angle. Slot 414 permits automatic operation of gear 541 without shifting plate 414 from its low blade angle position.

The propeller assembly with which the present invention is adapted to be used, may be, for example, like those disclosed in the patents to Blanchard and MacNeil Nos. 2,307,101 and 2,307,102, issued January 5, 1943. Fig. 17 shows somewhat diagrammatically a propeller hub and torque unit assembly of the type disclosed in

these patents. From the engine frame E there extends an engine driven shaft 501 which supports and drives a propeller hub 502 which supports an accumulator 503 containing a piston 504 movable toward the right from the position shown under the action of compressed gas forced into the accumulator through a check valve 505. The space, between the piston 504 and the fixed wall 506 of the accumulator, receives oil under pressure which forces piston 504 toward the left further to compress the gas to the left of the piston, thereby maintaining a supply of oil under pressure for the purpose of feathering and unfeathering the propeller blades. Duct 507, through which oil flows into the accumulator, is controlled by a valve to be described.

The hub 502 supports a plurality of blades 510, each having its root journaled in bearings 511. Each blade is rotated about its root axis by separate torque unit comprising a cylinder 512 attached to a blade root and having its upper end closed by cap 513 rotatably supported at its lower end by a bearing 514. Cylinder 512 cooperates with a piston 515 having external helical splines 516 cooperating with internal helical splines 517 of the cylinder 512 and having internal helical splines cooperating with external helical splines 518 of a relatively fixed member 519 supported by the hub 502. Pipes 520 and 521 lead respectively to the inner and outer ends of the cylinder 512 and are connected in a manner to be described with a distributing valve. The spiral splines are so constructed that inward movement of the piston 515 effects rotation of the cylinders 512 (clockwise looking outwardly) for the pitch increasing function; and outward movement of the piston 515 effects rotation of the cylinders 512 in opposite direction for the pitch decreasing function. The cylinders 512 are each connected with a bevel gear segment 522, each meshing with a master gear 523 supported by a bearing 524 carried by the hub 502, thereby equalizing the pitch changing movements of the blades.

The hub 502 supports a plate 530 which, as shown in Fig. 19, is secured by tubular nut 531. The plate 530 and its cover 532 (Fig. 17) provides a reservoir for hydraulic fluid. The engine shaft 501 is surrounded by a non-rotatable tube 533 concentric with the shaft and with the nut 531 (Fig. 19). Tube 533 is provided with a tang 534 (Fig. 17) received by a notch between brackets 535 attached to engine frame E. The plate 530 and its cover 532 provide bearings which maintain the concentricity of the tube 533, one of these bearings being shown at 536 in Fig. 19. Each bearing has a seal such as 537. Tube 533 provides an annular flange 538 which supports a plurality of shafts 539, each driven by a pinion 540 meshing with a ring gear 541 rotatably supported in any suitable manner by the sleeve 533. Ring gear 541 is provided with a handle or lever 541a which may be operated by a setting device which is under direct manual control or by the controller C.

Rotation of gear 541 by lever 541a or lever 541b effects rotary movements of shafts 539 for the purpose of obtaining blade pitch change. Each shaft 539 provides a screw 545 threaded into a grooved ring 546 slidably along the tube 533. Ring 546 receives a shoe 547 (Fig. 18) attached to a rod 548 guided for movement parallel to the shaft 501 by the plate 530. Shoe 547 connected by screw 549 with a bar 550 having a slot 551 which receives a shoe 552 provided by a pin 553 which swivels in a carriage 554 supported by roll-

ers 555 slidable in ways provided by channel brackets 556 attached by screws 557 to a valve body 558 attached by screws 559 to the plate 533. The valve body 558 is part of a distributing valve unit 560 comprising a valve 561 slideable in a valve sleeve 562 having ports 563, 565 and 567 connected by annular grooves 564, 566 and 568 respectively with holes 569, 570 and 571 respectively. Hole 570 is connected in a manner to be described with a pressure pump. Hole 569 is connected with passages 521 and hole 571 is connected with passages 520. The position of valve 561 is determined by the position of carriages 554 which carries a roller 572 engageable with a lever 573 pivotally supported by pin 574 carried by a screw 575 attached to the valve body 558. Lever 573 is provided with a notch 576 receiving a pin 577 attached to the valve 561. Since centrifugal force acts upon the valve 561 as indicated by arrow 561a, Fig. 19, the lever 573 remains in engagement with the roller 572 while the propeller hub is rotated. Hence, no spring is required to hold the lever 573 against the roller 572. In the disclosed apparatus, when ring gear 541 is rotated counterclockwise in Fig. 17 or clockwise in Fig. 1, an increase of blade angle is effected. Pinions 540 and shafts 539 rotate counterclockwise thereby causing the grooved ring 546 to move toward the left, thereby moving the carriage 554 toward the left. As roller 572 moves toward the left, centrifugal force causes the valve 561 to move upwardly, thereby connecting holes 570 and 569 which causes pressure fluid to flow through pipes 521 in order to force the piston 515 inwardly whereby blade pitch is increased. While the blades 510 are being rotated about their root axes in the direction of pitch increase, the valve 561 is being returned to a balanced position, closing ports 563 and 567 at which position the valve arrives when the demand for pitch increase has been satisfied. In order to accomplish this, the master bevel gear 523 is connected with a gear 580 (Fig. 21) which is retained by a plate 581 attached to the hub 502 and which meshes with a gear 582 pivotally supported by a screw 583 attached to a plate 584 supported by hub 502. Gear 582 meshes with gear 585 attached to a shaft 586 having a bearing and a boss 587 integral with the plate 584. Shaft 586 is connected with a coupling disc 588 connected by a screw 589 with a coupling disc 590 attached to a shaft 591 journaled in a bearing 592 carried by the plate 530 and retained by a nut 593 threaded on the bearing 592 as shown in Fig. 21. Shaft 591 is provided with a helical groove 595 which receives a ball 596 carried by a member 597 which serves as a nut and travels along the helical or screw-threaded groove 595. Nut 597 provides a stud 598 passing through a slot 599 in bar 550 and retained by a nut 600. The back lash in the gears 582 and 585 is taken up by spring 601 having one end received by a notch 602 in the boss 587 and the other end received by notch 603 in the hub of the coupling disc 588. The spring 601 is initially wound up in order to spring-load the gears 580, 582 and 585. Coupling screw 583 passes through an elongated arcuate hole 590a in the disc 590, thereby providing for angular adjustment between the coupling discs 588 and 590.

When carriage 554 is in the position shown in Fig. 19 and in full section lines (Fig. 20), the valve 561 is in neutral position blocking ports 563 and 567 so that the torque units will not operate. One set of conditions which places

valve 561 in neutral position, is that which exists when screw 549 and stud 598 are located as shown in Fig. 20. These are the conditions for minimum positive or maximum negative pitch. To decrease pitch negatively and increase pitch positively, gear 541 is rotated counterclockwise thereby causing ring 546 and carriage 554 to move left from the position shown in Fig. 18. The demand for pitch increase, positively, may be such as to place screw 549 in position 549' and bar 550 in position 550' and carriage 554 in position 554' (Fig. 20). This will effect blade angle increase, positively, in the manner described. During blade angle increase, the master gear 523 rotates counterclockwise as indicated by arrow 523a in Fig. 17 or clockwise in Fig. 22, as indicated by arrow 523b. Therefore the shaft 586 will rotate clockwise in Fig. 22, thereby causing the screw 595 to rotate counterclockwise as indicated by arrow 595a when viewed from the direction of arrow 595b (Fig. 21). Therefore, while the blades are being rotated to increase pitch, the nut 597 will be moving down in Figs. 20 and 21 thereby carrying the stud 598 to the position 598' which causes the carriage 554 to be brought back into position shown in full lines in Fig. 20, thereby returning the valve 561 in balanced position. If the movement of ring 546 had been such as to cause the screw 549 to move to 549'', the carriage 554 would have been moved further than 554', thereby demanding a greater blade angle change which would cause the stud 598 to move to 598'' before the valve 560 is returned to balanced position. It is therefore apparent that for every position of the ring 546 there is a definite blade angle. Consequently, for every position of lever 561a, there is a definite blade angle position. The mechanism shown provides for adjustment of blade angle in a range of approximately 120°.

The flange 538 of sleeve 533 (Fig. 17) provides a stationary gear 610 meshing with a gear 611 which drives a pump PP while the propeller hub is rotating. The outlet of pipe p of pump PP is connected with the passage 578 of the distributing valve 560. Pipe p is connected by pipe p₁ with a pressure control unit PC connected by pipe p₂ with an accumulator control valve unit AV. The pressure control unit PC comprises a valve rod 630 having a dashpot head 631 received by a cylinder 632 connected with pipe p₁ and urged outwardly by centrifugal force acting in the direction of arrow 633 and by spring 634 in opposition to fluid pressure acting upon the lower surface (Fig. 17) of a piston valve 635 received by a cylinder 636 and controlling a relief port 637. The inner end of cylinder 636 is connected by pipe 638 with pipe 521 as shown also. Valve 635, being responsive to centrifugal force, causes the pressure in line p to increase as speed increases and this pressure is increased also when cylinder 636 receives pressure from the pipe 521 which is under pressure when there is a demand for pitch increase.

The unit PC includes also a minimum pressure control valve provided by a rod 640 having lands 641 and 642 for controlling the connection between port 637 and a discharge port 643. The rod 640 has a dashpot head 644 engaged by a spring 645 located in a cylinder 646 connected with cylinder 632. The force of spring 645 is opposed by the fluid pressure acting upon the under side of valve land 641 (Fig. 17). The pressure available in pipe p will be limited to a minimum value by movement of rod 640 to a

position for connecting the ports 637 and 643, valve 635 having opened port 637. Up to a certain rotative speed of the hub, the pressure is limited to a minimum value in order that the accumulator will be fully charged within a short time even while the engine is operating at low speed. This minimum pressure is sufficient for the pitch-decreasing function of the torque units. As propeller speed increases, valve 635, being under control by centrifugal force, requires greater line pressure to cause the opening of the port 637. Therefore the pressure increases in pipe p above the minimum in order to make available the pressure required for the pitch-increasing function which requires greater pressure with increase of speed.

While rod 640 of unit PC is shown parallel with rod 630 which is under the action of centrifugal force, it will be understood that rod 640 is not controlled by centrifugal force but is actually located at right angles to rod 630. The units PC and AV are fully described in the co-pending application of David A. Richardson, Serial No. 613,563, filed August 30, 1945.

For the understanding of the present invention, it is sufficient to state that the accumulator control valve unit AV has a check valve 650 which normally blocks flow from the accumulator 503 to pipe p_1 . When feathering is required, ring 546 is moved to the extreme left to cause a roller 651 (carried by a shoe 652 received in the groove of ring 546) to engage cam 653 on a lever 654 and to effect downward movement of said lever and of a rod 655, thereby opening the check valve 650. Pressure oil then flows from the accumulator to underside (in Fig. 17) of a piston 656, thereby effecting the opening of a valve 657 so that the accumulator may discharge to pipe p_1 through a by-pass around the check valve. During this discharge the valve 657 is held open by oil pressure against the underside (in Fig. 17) of a piston 658. As feathering is completed, the pressure differential between the pressure in pipe p_1 and the pressure against the underside of piston 658 decreases and spring 659 closes valve 657. Cam 653 having been momentarily contacted by roller 651 during movement of ring 546 to the extreme left, check valve recloses. Therefore discharge of the accumulator is prevented until it is desired to use accumulator pressure to assist in the unfeathering operation. This is effected by right movement (in Fig. 17) of ring 546 which effects momentary opening of check valve 650; and discharge of the accumulator into pipes p_1 and p takes place.

If feathering is required on any type of engine-propeller power plant with which the present controller is used, feathering would be controlled manually. If the controller interferes with manual control for feathering, the link 412 can be made with telescopically collapsible parts which a compression spring normally holds extended.

While the embodiment of the present invention as herein disclosed, constitutes a preferred form, it is to be understood that other forms might be adopted, all coming within the scope of the claims which follow.

What is claimed is as follows:

1. Engine control apparatus for use with an engine having means for increasing or decreasing its load comprising a movable member for controlling the engine loading means, a speed responsive device driven by the engine, manually

operable engine power selecting means for adjusting the device to control for a selected speed and for moving the member to obtain engine loading corresponding to the selected speed, and means under control by the device for adjusting the member independently of the manual adjustment by the power selecting means to change the engine loading in case engine speed deviates from selected speed.

2. Engine control apparatus for use with an engine having means for increasing or decreasing its load comprising a movable member for controlling the engine loading means, a mechanism for moving said member including a differential lever, a speed responsive device driven by the engine, manually operable engine power selecting means for adjusting the device to control for a selected speed and for moving the lever to move the member to obtain engine loading corresponding to a selected speed, and means under control by the device for moving the lever independently of the manual adjustment by the power selecting means to adjust the member to change the engine loading in case engine speed deviates from selected speed.

3. Engine control apparatus for use with an engine having means for increasing or decreasing its load comprising a movable member for controlling the engine loading means, a fluid pressure source, a fluid operated servo having a movable member operated by said source, a differential lever operatively connected with the servo member, a speed responsive device driven by the engine, manually operable engine power selecting means for adjusting the device to control for a selected speed and having a part connected with the lever to move it independently of the servo member, a mechanism for transmitting movement from the lever to the first member to obtain engine loading corresponding to the selected speed, and means under control by the device for controlling movement of the servo member to obtain movement of the lever and first member independently of the manual means to change the engine loading in case engine speed deviates from selected speed.

4. Engine control apparatus for use with an engine having means for increasing or decreasing its load comprising a movable member for controlling the engine loading means, a fluid pressure source, a fluid operated servo comprising a cylinder, a piston therein and a rod connected with the piston and passing through an end of the cylinder, a duct connecting the pressure source with the rod end of the cylinder, a second duct connected with the other end of the cylinder, a differential lever connected with the rod, a speed responsive device driven by the engine, manually operable engine power selecting means for adjusting the device to control for a selected speed and having a part operatively connected with the lever to move it independently of the piston, a mechanism for transmitting movement from the lever to the first member to obtain engine loading corresponding to the selected speed, and means under control by the device and operating in case engine speed deviates from selected speed to control flow of fluid into or out of the second duct in order to move said lever and member independently of the manual means to change the engine loading.

5. Engine control apparatus for use with an engine having means for increasing or decreasing its load comprising a movable member for controlling the engine loading means, a fluid

pressure source, a fluid operated servo comprising a cylinder, a piston therein and a rod connected with the piston and passing through an end of the cylinder, a duct connecting the pressure source with the rod end of the cylinder, a second duct connected with the other end of the cylinder, a differential lever connected with the rod, a speed responsive device driven by the engine, manually operable engine power selecting means for adjusting the device to control for a selected speed and having a part operatively connected with the lever to move it independently of the piston, a mechanism for transmitting movement from the lever to the first member to obtain engine loading corresponding to the selected speed, means under control by the device for effecting fluid flow into or out of the second duct at a rate equal to a factor (k_1) times speed error plus a factor (k_2) times rate of change of speed error, and means responsive to movement of said member for varying the factor k_2 .

6. Engine control apparatus for use with an engine having means for increasing or decreasing its load comprising a movable member for controlling the engine loading means, and engine operated flyweight governor, a spring opposing separation of the weights by centrifugal force, a fluid pressure source, a stabilizer cylinder, a piston therein, a lever connected with the piston and having an adjustable fulcrum, a fluid pressure source, valve-means normally blocking fluid flow into one end of the stabilizer cylinder from the source or out therefrom to drain when engine speed equals that for which the governor is adjusted, said valve-means comprising a valve operated by the governor and a follow-up valve operated by the lever whereby the stabilizer piston is displaced from equilibrium position an amount proportional to speed error and at a rate proportional to the rate of change in speed error, a duct connected with the other end of the stabilizer cylinder in which fluid will flow at the rate determined by the rate of movement of the stabilizer piston, a servo-motor having a cylinder, a piston and a piston rod outstanding through one end of the cylinder, a second duct connected with the other end of the cylinder and with the first duct, a valve operated by the lever for connecting the second duct with the source or with drain when speed error exists, manually operable engine power selecting means for adjusting the governor spring, mechanism actuated jointly by the servo-piston and said manually operated means for moving the member and means responsive to movement of the member for adjusting the fulcrum of the lever.

7. Engine control apparatus for use with an engine having means for increasing or decreasing its load comprising a movable member for controlling the engine loading means, an engine operated flyweight governor, a spring opposing separation of the weights by centrifugal force, a fluid pressure source, a stabilizer cylinder, a piston therein, a lever connected with the piston and having an adjustable fulcrum, a fluid pressure source, valve-means normally blocking fluid flow into one end of the stabilizer cylinder from the source or out therefrom to drain when engine speed equals that for which the governor is adjusted, said valve-means comprising a valve operated by the governor and a follow-up valve operated by the lever whereby the stabilizer piston is displaced from equilibrium position an amount proportional to speed error and at a rate

proportional to the rate of change in speed error, a duct connected with the other end of the stabilizer cylinder in which fluid will flow at the rate determined by the rate of movement of the stabilizer piston, a servo-motor having a cylinder, a piston and a piston rod extending through one end of the cylinder, the piston rod end of the cylinder being connected with the source, a second duct connected with the other end of the cylinder and with the first duct, a valve for connecting the second duct with the source or with drain when speed error exists, a second lever operatively connected with said valve and the first lever, means for adjusting the fulcrum of the second lever, manually operable engine power selecting means for adjusting the governor spring, mechanism actuated jointly by the servo-piston and said manually operated means for moving the member.

8. Engine control apparatus for use with an engine having means for increasing or decreasing its load comprising a movable member for controlling the engine loading means, a differential lever operatively connected with the member, a first actuator connected with the lever, a second lever actuator having two parts which sequentially engage portions of the lever at different distances from the first actuator as the second actuator is moved, a speed responsive device driven by the engine, means under control by said device for moving the first actuator to operate the lever and to adjust the member in case engine speed deviates from the speed for which the device is set, manually operable engine power selecting means for adjusting the device to maintain a selected speed and for operating the second actuator.

9. Engine control apparatus for use with an engine having means for increasing or decreasing its load comprising a movable member for controlling the engine loading means, a first actuator, a differential lever connected at one end with the first actuator and providing a surface at its other end portion for engagement by a second actuator, a mechanism operatively connecting an intermediate portion of the lever with the member, a second actuator comprising a lever and two parts carried thereby and movable sequentially into contact with portions of the differential lever surface which are located at different distances from the first actuator, a speed responsive device driven by the engine, means under control by said device for moving the first actuator to operate the lever and to adjust the member in case engine speed deviates from the speed for which the device is set, and manually operable means for setting the speed which the device is to maintain and for operating the second actuator to obtain engine loading corresponding to the speed setting.

10. Engine control apparatus for use with an engine having means for increasing or decreasing its load comprising a movable member for controlling the engine loading means, an hydraulic servo comprising a cylinder having a head end and a rod end, a piston and a piston rod extending through the rod end of the cylinder, a differential lever connected at one end with the piston rod, a manually operated actuator operatively connected with the differential lever, a mechanism for transmitting to the member movements of the differential lever effected by the piston rod and by manually operated actuator, a flyweight governor operated by the engine having a spring opposing movement of the

weights by centrifugal force, manually operable engine power selecting means for adjusting the spring to select the speed which the governor is set to maintain and for moving the manually operated actuator to obtain through adjustment of said member engine loading corresponding to the speed setting of the governor, first and second valve guides having inlet and outlet ports, a fluid pressure source connected with said inlet ports and with the rod end of the servo cylinder, a stabilizer cylinder, a piston therein, a duct connecting the outlet port of the first guide with one end of the stabilizer cylinder, ducts connecting the head of the servo-cylinder with the other end of the stabilizer cylinder and with the outlet port of the second valve guide, a sleeve valve in the first valve guide and having inlet and outlet ports connected respectively with the inlet and outlet ports of its valve guide and having a passage to drain, a spool valve located within the sleeve valve and operated by the governor when speed error exists either to connect the inlet and outlet ports of the sleeve valve or to block the inlet port and to connect the outlet port with drain, means for effecting movement of the sleeve valve in response to movement of the stabilizer piston, a valve in the second valve guide operable when speed error exists either to connect the inlet and

outlet ports of its valve guide or to block the inlet port and connect the outlet port with drain, and means for effecting operation of the last mentioned valve in response to movement of the sleeve valve.

CLIFFORD L. MUZZEY.
